ELASTIC FLUID POWER PLANT

Filed Dec. 8, 1938

UNITED STATES PATENT OFFICE

2,204,139

ELASTIC FLUID POWER PLANT

Paul H. Knowlton, Jr., Schenectady, N. Y., assignee to General Electric Company, a corporation of New York

Application December 8, 1938, Serial No. 244,626

9 Claims. (Cl. 66—70)

The present invention relates to elastic fluid power plants in which elastic fluid such as steam or mercury vapor is produced in an elastic fluid generator and supplied to consuming apparatus.

- 5 The elastic fluid generator usually comprises a boiler in which liquid is heated and evaporated, a furnace for heating the boiler and means for supplying and controlling the supply of combustibles to the furnace. The consuming apparatus may 10 comprise an elastic fluid turbine, means for conducting and regulating the flow of elastic fluid to the turbine and means including a condenser for receiving the exhaust fluid from the turbine. The means for supplying and regulating the supply 15 of feed fluid to the boiler and the means for supplying combustibles to the furnace may include pumps and a blower driven by an auxiliary elastic fluid turbine receiving operating fluid from the boiler.

- 20 My present invention is an improvement over the invention of the G. B. Warren application, Serial No. 244,624, filed December 8, 1938; and assigned to the General Electric Company, which invention was made by the said G. B. Warren 25 prior to my invention. I therefore do not herein claim anything shown or described in said Warren application, which is to be regarded as prior art with respect to this present application.

- The object of the present invention is to provide 30 an improved arrangement for power plants of the type specified whereby the control and regulation of the various apparatus is accomplished in a simple manner.

- For a consideration of what I believe to be 35 novel and my invention, attention is directed to the following description and the claims appended thereto taken in connection with the accompanying drawing.

- A power plant system embodying my invention 40 is shown in the drawing in a diagrammatic form only, omitting, for the sake of clarity, such supplemental apparatus as pilot valves, valve actuating motors, and other incidental control auxiliaries which may be supplied as desired by one 45 skilled in the art.

- In the drawing, 10 indicates an elastic fluid 50 generator comprising a furnace and a boiler of the pumped through type which supplies elastic fluid through a conduit 11 to the consuming apparatus. Elastic fluid from the conduit 11 is admitted through a suitable control valve 12, preferably of the sectional admission type, to an auxiliary turbine 13 provided for driving the elastic fluid generator auxiliaries. The exhaust fluid 55 from the auxiliary turbine is conducted through

a conduit 14 to a main turbine 15 through a suitable admission controlling valve 16. The main turbine 15 may be utilized for driving any suitable load, not shown, connected to the shaft 17 extending therefrom. The exhaust fluid from the main turbine may be received by suitable condensing apparatus 18 indicated in this instance as being of the surface cooled type. The condensate from the condenser may be conducted by means of a connection 19 to a storage reservoir 20 or hot-well 20 from whence it may be returned by means of conduit 21, booster pump 22, conduit 23, boiler feed pump 24, and conduit 25 to the boiler of the elastic fluid generator 10. The booster pump 22 is illustrated as being of the 25 centrifugal type and may be driven by any suitable motor, not shown. The boiler feed pump 24, preferably of the positive displacement type, is shown diagrammatically as comprising a cylinder 26 having a reciprocating piston 27 arranged therein provided with a stem 28, the end of which is adapted to be engaged by a cam means 29 driven by the shaft 30 of the auxiliary turbine 13. The piston may be biased to an upper position by a spring means 31. Fluid flow through 30 the pump is controlled by means of check valves 32 and 33 suitably arranged in the inlet and outlet ports respectively of the pump. It is obvious that any suitable type of boiler feed pump may 35 be used for applying suitable pressure to the liquid to be forced into the boiler and in addition, it is understood that while I illustrated the pump 24 as being driven directly from the shaft 30, it may be desirable to provide a suitable speed reduction gearing in the driving connection.

The auxiliary turbine, in addition to driving the boiler feed liquid pump 24, is also arranged for driving additional boiler auxiliaries, such as the combustion air blower 34 and the furnace fuel pump 35. For the sake of clarity, as with the boiler feed liquid pump 24, the combustion air blower and the fuel pump are shown as being directly driven by the auxiliary turbine shaft 30 although it is understood that suitable speed reduction gearing may be used in the driving connections to these devices as desired. The combustion air blower is arranged for drawing air through an inlet 36 and discharging it through a conduit 37 to the furnace of the elastic fluid generator 10. The fuel pump 35 receives fuel 40 through the conduit 38 from the storage tank 39 and discharges it through a conduit 40 to the furnace burner.

The valves 12 and 16 controlling the admission 45 of elastic fluid into the auxiliary and main tur- 50

bines respectively are connected together for simultaneous movement and are adapted to be adjusted in accordance with the condition of load on the main turbine. The sectional admission 5 valve controlling the flow of elastic fluid to the auxiliary turbine 13 is biased to the closed position by spring means 12'. This valve is adapted to be operated to the open position by downward movement of a link 41, the lower end of which 10 is pivotally connected to one end of a fulcrumed lever 42, the other end of the lever 42 being connected as by link 43 to the end of the stem 44 15 extending from the valve 16.

A suitable form of speed governing mechanism 15 may be employed for adjusting the elastic fluid admission valves so as to maintain a substantially constant speed of the main turbine 15 under varying conditions of load. As shown, a speed governor 45, adapted to be driven through gearing 46 from the extension 47 of the main turbine 20 shaft, is arranged for controlling the position of the valves 12 and 16 through a suitable hydraulic operating mechanism including a pilot valve 48 and a servo-motor 49. As shown, the pilot valve 48 comprises a cylinder 50 having valve 25 heads 51 and 52 slidably arranged therein, the valve heads being mounted in a spaced apart relationship upon a stem 53, the end of which stem is connected for movement by the speed governor 30 45. The servo-motor 49 comprises a cylinder 54 having a piston 55 slidably arranged therein. The chambers in the cylinder 54 above and below the piston 55 communicate with the pilot valve 35 through connections 56 and 57 respectively. Operating fluid for the servo-motor, such as oil under 40 pressure, is adapted to be supplied to the pilot valve through connection 58 and is drained therefrom through connections 59 and 60. A stem 61 secured to the piston 55 of the servo-motor 49 is connected, as at 62, to an end of a lever 63 which 45 in turn is pivoted intermediate its ends to a stationary part 64. The other end of the lever 63 is connected as by a link 65 to an arm 66 secured to the valve stem 44.

Except as modified by the supplemental control 45 apparatus to be described later, the major changes in the output of the various auxiliaries to the elastic fluid generator are automatically made in accordance with the demand for elastic fluid of the main turbine. By the proper adjustment of 50 the interconnection between the admission valves 12 and 16, the speed of the auxiliary turbine may be caused to vary in accordance with the supply of elastic fluid to the main turbine and since the 55 boiler auxiliaries, that is, the boiler feed liquid pump, the combustion air blower and the fuel pump, are arranged to be driven through connections from the auxiliary turbine shaft, the output of these units will vary substantially in proportion to the speed thereof. Assume, first, that the 60 power plant is operating in equilibrium with normal conditions obtaining, that is, with the main turbine operating with a constant load and the elastic fluid generator auxiliaries driven at such 65 a speed as to cause the proper amount of elastic fluid to be generated as is required for the particular load. Now assume that the load on the main turbine for some reason increases causing it to decrease slightly in speed. The flyweights of 70 the governor 45 will drop a certain amount moving the pilot valve heads upwardly establishing communication between the supply of operating fluid and the upper chamber of the servo-motor 49 whereupon the piston thereof will be forced 75 downwardly. This movement of the servo-motor

causes a counterclockwise rotation of the lever 63 which in turn will impart an opening movement to the main turbine valve 16. This movement will also be imparted through the link 43 to the fulcrumed lever 42 rotating it in a clockwise direction to move the auxiliary turbine valve 12 simultaneously to a more opened position. Normally, due to the proper adjustment of the movable pivot about which the lever 42 is fulcrumed, the valve 16 will be moved to a relatively wider 10 opened position than the valve 12 so that the back pressure to the auxiliary turbine 13 will be relatively lower with respect to the admission pressure thereto in the new position of adjustment than in the previous position. Thus the pressure 15 drop through the auxiliary turbine is slightly greater in the new position of the valves than previous to the change whereby the speed thereof is proportionately increased to cause an increased output of the auxiliaries which increased output 20 will be substantially in proportion to the increased demand for elastic fluid of the main turbine. Conversely, upon a decrease in load on the main turbine, the speed of the auxiliary turbine will be decreased by a reverse operation of the control 25 mechanism described above to decrease the output of the boiler auxiliaries.

Since the speed of the auxiliary turbine is determined by the pressure drop experienced by the elastic fluid in passing therethrough, supplemental means are provided for controlling such pressure drop by adjusting the connection between the valves 12 and 16 so that the relative ratio of the opening and closing movement of these valves with respect to each other is varied as required 30 by conditions obtaining with respect to the elastic fluid generator. This is accomplished, according to the invention, by the provision of means responsive to the flow of elastic fluid in the main supply conduit and also to the level of liquid 35 in the boiler. As indicated in the drawing, the lever 42 connecting the valve operating members 41 and 44 is pivoted intermediate its ends at 40 67 to an adjustable support 68. The lever 42 is provided with a longitudinal slot 69 in which the 45 pivot pin is adapted to slide as the support is moved. The support 68 is mounted for sliding engagement upon a suitable base 70. The lengths of the valve operating connections are so adjusted with respect to the lever 42 that when the 50 valves are in their wide opened position, the lever 42 will lie in a position substantially parallel with the base 70. With the valves in some mid position, the lever 42 will assume some angular position with respect to the base such as that indicated. The pivot support is adapted to be adjusted in response to variations in pressure drop 55 across a variable orifice or valve 71 in the boiler feed liquid conduit 23. A differential pressure responsive device 72 is connected across the valve 60 71, which comprises a casing 73 having a flexible diaphragm 74 therein forming chambers on opposite sides thereof with the casing. The chamber on the right is in communication by conduit 75 with the conduit 23 ahead of the valve 71, as regards the direction of flow therethrough, while the left chamber is in communication by conduit 76 with the conduit 23 behind the valve 71. A biasing spring 77 is suitably arranged between the left side of the diaphragm and the casing for 70 determining the operating characteristics of the device. The flexible diaphragm is connected as by a stem 78 to pilot valve heads 79 and 80 slidably arranged within the pilot valve cylinder 81. The operating motor for the adjustable pivot 75

comprises a cylinder 82 having a piston 83 slidably arranged therein which is connected as by a stem 84 to the adjustable pivot support 68. Operating fluid, such as oil under pressure, is supplied to the 5 pilot valve through conduit 85 from whence it passes, depending upon the position of the pilot valve heads, through either of the connections 86 or 87, to the cylinder 82 on one side or the other of the piston 83. Operating fluid is drained from 10 the pilot valve through either of the connections 88 or 89.

The biasing spring of the pressure responsive device 72 has such characteristics that the diaphragm assumes a central position upon a predetermined pressure drop obtaining across the valve 71 regardless of the degree of opening of said valve. The valve 71 is adapted to be adjusted in accordance with the elastic fluid flow through the main supply conduit 11 and also in accordance with the quantity of liquid in the boiler. This control system includes a flow responsive device 90 and a liquid level responsive device 91 differentially connected together. As shown, the elastic fluid flow responsive device 90 comprises 25 a casing 92 having a flexible diaphragm 93 therein forming chambers on either sides thereof with the casing. The chamber on the left is in communication by a connection 94 with the elastic fluid conduit 11 ahead of a nozzle 95 provided 30 therein. The chamber on the right is in communication as by connection 96 with the elastic fluid conduit 11 behind the nozzle 95, as regards the direction of flow therethrough. A biasing spring 97 is arranged between the right side of 35 the diaphragm and the casing for determining the operating characteristics of the device. The liquid level responsive device 91 comprises a casing 98 having a flexible diaphragm 99 therein forming chambers on either side thereof with the casing. The quantity of liquid in the boiler is measured as by a suitable float means 100 arranged in a drum 101 thereof. An indication of the level of the liquid therein is transmitted from the float through a link 102 to a lever 103 pivoted 40 to a stationary part 104. Fluid filled collapsible bellows devices 105 and 106 are arranged on opposite sides of the lever 103 for transmitting the liquid level indication to the device 91, the bellows 105, above the lever 103, being in communication 45 as by conduit 107 with the chamber on the right, while the bellows 106 is in communication as by conduit 108 with the chamber on the left of the device 91. The stems 109 and 110 connected to the diaphragms 93 and 99 of the devices 90 and 50 91, respectively, are connected together as by a floating lever 111 which in turn is pivotally connected at an intermediate point 112 to a lever 113 which in turn is pivoted at one end to a stationary part 114. The other end of the lever 113 is 55 pivotally connected as by a link 115 to an operating lever 116 of the valve 71.

The mode of operation of this regulating apparatus is as follows: assume, as before, that the system is operating in equilibrium with normal 60 conditions obtaining and that for some reason the load on the main turbine has increased causing the admission valves 12 and 16 to be actuated to a more opened position in accordance with the increased demand. The increased flow of elastic 65 fluid through the main supply conduit 11 will cause a decrease in pressure on the after side of the nozzle 95, and hence, a corresponding decrease in pressure in the chamber on the right side of the diaphragm of the flow responsive device 90 causing the stem 109 thereof to be moved

to the right. If the water level in the drum 101 remains normal the device 91 will be inactive whereupon the lever 111 will be rotated in a clockwise direction causing the pivotal connection 112 with the lever 113 to be moved to the right and through the arm 115 cause the valve 71 to be moved to a more opened position. Assuming that upon the change of position of the admission valves, 12 and 16, the auxiliary turbine 13 has not increased in its speed in proportion to the increased elastic fluid flow through the supply conduit 11 and that as a consequence the output of the feed liquid pump 24 has not increased in proportion to the opening movement of the valve 71 whereupon the pressure drop 10 thereacross has decreased below the predetermined value, the pressure on the left side of the diaphragm of the device 72 will thereupon increase causing it and the pilot valve heads connected thereto to be moved to the right. Upon 15 this movement operating fluid will be supplied to the servo-motor associated therewith to move the piston 83 thereof and the movable pivot support 68 connected thereto to the left. The pivot pin 67 will be moved in the slot 89 of the lever 42 20 causing the lever 42 to pivot about its left end in a counterclockwise direction moving the admission valve 12 to a slightly more closed position. This movement of the valve 12 will result in a decrease of supply of elastic fluid available for 25 the main turbine 15 whereupon through the governor mechanism associated therewith the valve 16 will be moved to a further opened position. As the valve 16 is further opened, the pressure in the conduit 14 will decrease resulting 30 in a greater pressure drop through the auxiliary turbine 13 causing it to increase in speed and accordingly increase the speed or output of the boiler feed liquid pump 24. The speed of the auxiliary turbine 13 will in this manner be increased until the pressure drop across the valve 71 assumes the predetermined constant value upon the occurrence of which condition the diaphragm 74 of the device 72 will assume its central position moving the pilot valve heads as 35 associated therewith to the neutral position arresting the movement of the servo-motor associated therewith and the movable pivot support 68. The auxiliary turbine will thus be regulated 40 for the proper speed and the system will be 45 stabilized for the new condition of load.

Conversely, if the readjustment of the admission valves 12 and 16 upon an increased load on the main turbine results in an excessive increase of speed of the auxiliary turbine causing the 55 output of the boiler feed liquid pump 24 to increase disproportionately as regards the new position of the valve 71, the pressure drop thereacross will be greater than the predetermined constant value. Accordingly, the pressure in the 60 chamber on the left of the diaphragm 74 of the device 72 will drop causing the diaphragm, and the pilot valve heads 79 and 80 connected thereto to be moved to the left. The piston of the servo-motor associated therewith will be moved to the 65 right causing the movable pivot support 68 to be moved therewith rotating the lever 42 in a clockwise direction and actuate the admission valve 12 to a more opened position. Upon the resultant increase of elastic fluid flow therethrough, the 70 valve 16 will be moved to a somewhat more closed position upon the consequential overspeeding of the main turbine 15. Accordingly, the back pressure to the auxiliary turbine 13 will be increased reducing the pressure drop 75

thereacross to somewhat decrease the speed thereof and consequently the speed and output of the boiler feed liquid pump 24. This manner of regulation will be continued until the pressure drop across the valve 71 is re-established at its predetermined constant value whereupon the diaphragm 74 of the device 72 will reassume its normal neutral position and the system stabilized as before.

It will be noted that the valve 71 is also connected for adjustment in accordance with the level of the liquid obtaining in the boiler drum 101. Assume that the level of the liquid therein should fall below a predetermined position causing the link 102 to move downwardly rotating the lever 103 in a clockwise direction. Due to the accompanying compression of the bellows device 106 and the expansion of the bellows device 105, the pressure in the chamber on the left of the diaphragm 99 of the device 91 will increase and the pressure on the right thereof will decrease moving the diaphragm and the stem 110 connected thereto to the right. The levers 111 and 113 will be moved thereby in a counterclockwise direction to actuate the valve 71 to a more opened position. In a manner similar to that outlined above, the admission valves 12 and 16 will be adjusted so as to increase the speed of the auxiliary turbine 13 and, accordingly, the speed and the output of the boiler feed liquid pump 24 to re-establish the predetermined level of liquid in the boiler drum. Upon such re-establishment of the predetermined level, or upon a level higher than the predetermined position obtaining in the boiler drum, the reverse operation of the apparatus will take place to move the valve 71 to a more closed position to slightly decrease the speed of the auxiliary turbine and the supply of feed liquid to the boiler. By the interconnection of the devices 90 and 91 through the floating lever 111, as shown, the valve 71 in the boiler feed liquid conduit 23 will be adjusted in accordance with the differential indication of the two devices.

The supply of combustibles to the furnace of the elastic fluid generator is further regulated in accordance with the variations of the pressure of elastic fluid in the main supply conduit 11. As indicated in the drawing this is accomplished by means including a pressure responsive device comprising a cylinder 117 having a piston 118 arranged therein, the left end of which cylinder is in communication with the supply conduit 11 by a conduit 119 extending from the conduit 96. A stem 120 secured to the piston 118 is pivotally connected to an arm 121 arranged for operating a damper 122 in the combustion air conduit 37. The piston 118 is biased against the elastic fluid pressure by means of a spring 123 substantially as shown. The proper ratio between the air passed by the damper 122 to the furnace and the fuel supplied to the furnace is regulated by means including flow responsive devices 124 and 125. The device 124 comprises a casing 126 having a flexible diaphragm 127 arranged therein forming chambers on opposite sides thereof with the casing. The chamber on the left of the diaphragm is in communication by conduit 128 with the air supply conduit 37 ahead of a nozzle 129 provided therein. The chamber on the right of the diaphragm is in communication by conduit 130 with the air supply conduit 37 behind the nozzle 129 as regards the direction of air flow therethrough. Similar to the device 124, the device 125 comprises a cas-

ing 131 having a flexible diaphragm 132 arranged therein forming chambers on the opposite sides thereof with the casing. The chamber on the right is in communication by conduit 133 with the fuel supply conduit 40 ahead of a nozzle 134 provided therein. The chamber on the left is in communication by conduit 135 with the fuel supply conduit 40 behind the nozzle 134 as regards the direction of fuel flow therethrough. The stems 136 and 137 secured to the diaphragms 127 and 132 of the devices 124 and 125, respectively, are connected together by means of a floating lever 138. The floating lever is pivotally connected intermediate its ends as at 139 to one end of a lever 140 which is pivoted at the other end to a stationary part 141. Movement of the lever 140 is imparted by a connection link 142 to the valve 143 arranged in the fuel supply conduit 40 between the fuel pump 35 and the nozzle 134. In the event that the output of the fuel pump 35 is in excess of that allowed to pass the valve 143 provision is made by means of conduit 144 for bypassing the excess fuel from the conduit 40 back to the fuel storage tank 39. A pressure relief valve 145 is arranged in the bypass conduit which may be adjusted to open upon a predetermined pressure obtaining in the conduit 40 between the fuel pump 35 and the valve 143.

In the operation of the last described apparatus, as the pressure in the elastic fluid supply conduit 11 is decreased, the damper valve 122 in the combustion air conduit 37 is moved to a more opened position whereupon the supply of combustion air to the furnace is increased. As the flow of air to the furnace is increased, the proper ratio between the air and fuel is maintained by the cooperation of the flow measuring devices 124 and 125.

As the flow of air through the nozzle 129 in the air supply conduit 37 increases, the pressure in the chamber to the left of the diaphragm 127 of the device 124 will increase causing the stem 136 secured thereto to be moved to the right. Accordingly, the lever 138 will be rotated about its lower end moving the pivotal connection 139 with the lever 140 to the right which in turn will operate the valve 143 in the fuel supply line 40 to a more opened position. As the fuel flow through the nozzle 134 is increased, the pressure on the right side of the diaphragm 132 of the device 125 will be increased whereupon the stem 137 connected thereto will move to the left carrying with it the lower end of the floating lever 138 effecting a throttling action of the valve 143.

Conversely, upon the rise in pressure of elastic fluid in the supply conduit 11, the damper 122 in the combustion air conduit will be throttled to a more closed position which in turn will cause a proportionate decrease in the supply of fuel to the furnace burner.

From the foregoing description it will be seen that the entire power plant system is substantially automatically regulated in response to changes in load on the main turbine. During normal operation, the adjustment of the interconnection between the auxiliary and main turbine admission valves which results in the proper speed changes of the auxiliary turbine for the different loads of the main turbine becomes substantially fixed. It is understood that during normal load variations the level of liquid in the boiler drum will remain substantially constant since the liquid supplied thereto by the boiler feed pump is adjusted in accordance with the varia-

tions of flow of elastic fluid from the boiler. Upon the occurrence of abnormal conditions, the liquid level in the boiler drum may vary one way or the other whereupon the output of the feed liquid pump will be adjusted independently of the load on the main turbine to reestablish the predetermined level. During all load conditions the supply of combustibles to the furnace is automatically regulated as to maintain a substantially constant predetermined boiler pressure.

Having described the method of operation of my invention together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. In a power plant, the combination of an elastic fluid generator comprising a furnace, a boiler, a fuel pump, a combustion air blower and a boiler feed pump, an auxiliary turbine for driving said pumps and said blower, a conduit for conducting elastic fluid from said boiler to said auxiliary turbine, a main turbine, a conduit for conducting elastic fluid from said auxiliary turbine to said main turbine, admission valves for controlling the supply of elastic fluid to each of said turbines, means for adjusting said valves in accordance with the load on said main turbine, and means for supplementally adjusting the admission valve of said auxiliary turbine in accordance with a condition of operation of said elastic fluid generator.

2. In a power plant, the combination of an elastic fluid generator comprising a furnace, a boiler, a fuel pump, a combustion air blower, and a boiler feed pump, an auxiliary turbine for driving said pumps and said blower, means for conducting elastic fluid from said boiler to said auxiliary turbine, a valve for controlling the admission of elastic fluid to said auxiliary turbine, a main turbine, conduit means for conducting elastic fluid from said auxiliary turbine to said main turbine, a valve for controlling the admission of elastic fluid to said main turbine, means for adjusting said main turbine admission valve in accordance with the load on said main turbine, means connecting said auxiliary turbine admission valve for operation with said main turbine admission valve, means for adjusting the relative movement of said auxiliary turbine admission valve with respect to movements of said main turbine admission valve for varying the regulation of said auxiliary turbine.

3. The combination of an elastic fluid generator comprising a boiler, and a furnace, a main turbine, a conduit for conducting elastic fluid from said generator to said turbine, a valve for controlling the admission of elastic fluid to said turbine, means for regulating said admission valve in response to a load condition of said main turbine, a boiler feed pump, a fuel pump, a furnace draft blower, an auxiliary turbine arranged in said elastic fluid conduit ahead of said main turbine for driving said pumps and blower in accordance with the elastic fluid demand by said main turbine, an admission valve for said auxiliary turbine, an interconnection between said auxiliary turbine admission valve and said main turbine admission valve regulating means, and means for adjusting said interconnection whereby said auxiliary turbine admission valve may be supplementally regulated relative to said main

turbine admission valve in response to a condition of operation of said elastic fluid generator.

4. In a power plant, the combination of an elastic fluid generator comprising a furnace, a boiler, means for supplying combustibles to said furnace, a boiler feed pump, an auxiliary turbine for driving said pump and said combustibles supplying means, conduit means for supplying elastic fluid from said boiler to said auxiliary turbine, valve means for controlling the admission of elastic fluid to said auxiliary turbine, a main turbine adapted to receive elastic fluid from said auxiliary turbine, valve means controlling the admission of elastic fluid to said main turbine, means for adjusting said main turbine admission valve means, means connecting said auxiliary turbine admission valve means for actuation with said main turbine admission valve means, means for regulating the relative movement of said auxiliary turbine admission valve means with respect to movements of said main turbine admission valve means in response to variations in elastic fluid flow from said boiler and in response to variations in the liquid level in said boiler.

5. In a power plant, the combination of an elastic fluid generator comprising a boiler, a boiler feed pump, an auxiliary turbine for driving said pump, a conduit for conducting elastic fluid from said boiler to said auxiliary turbine, a valve for controlling the admission of elastic fluid to said auxiliary turbine, a main turbine, a conduit for conducting elastic fluid from said auxiliary turbine to said main turbine, a valve for controlling the admission of elastic fluid to said main turbine, actuating means responsive to a load condition of said main turbine for simultaneously adjusting said admission valves, a conduit for conducting boiler feed liquid to said boiler feed pump, a variable orifice in said last mentioned conduit, said orifice being adjustable in response to elastic fluid flow from said boiler and means responsive to variations in pressure drop across said variable orifice for adjusting the relative movement of said auxiliary turbine admission valve by said actuating means with respect to movement of said main turbine admission valve.

6. In a power plant, the combination of an elastic fluid generator, a liquid feed pump, an auxiliary turbine for driving said pump, a conduit for conducting elastic fluid from said generator to said auxiliary turbine, an admission valve for said auxiliary turbine, a main turbine connected for receiving elastic fluid from said auxiliary turbine, an admission valve for said main turbine, means interconnecting said main turbine and auxiliary turbine admission valves, means for simultaneously adjusting both of said admission valves in accordance with a load condition of said main turbine, and means for adjusting said interconnection in response to a differential indication of the flow of elastic fluid from said generator and of the liquid level in said generator.

7. In a power plant, the combination of a boiler, boiler feeding auxiliaries, an auxiliary turbine for driving said auxiliaries, conduit means for conducting elastic fluid from said boiler to said auxiliary turbine, a main turbine adapted to be driven by the exhaust fluid from said auxiliary turbine, admission valves for each of said turbines, a governor driven by said main turbine, adjustable means connecting said admission valves for simultaneous actuation by said governor, and means including said adjustable con-

necting means for supplementally adjusting said auxiliary turbine admission valve in response to a condition of operation of said boiler.

8. The combination of a first elastic fluid turbine, conduit means for conducting elastic fluid to said turbine, a valve for controlling the admission of elastic fluid to said turbine, a second turbine, conduit means for conducting the elastic fluid exhaust from said first turbine to said second turbine, a valve for controlling the admission of elastic fluid to said second turbine, means including a lever mounted on a pivotal support interconnecting said first and second turbine admission valves, governor means for adjusting said valves in accordance with a load condition of one of said turbines, and means for adjusting the pivotal support with respect to said lever for varying the relative adjustment between said ad-

mission valves upon actuation of said governor means.

9. The combination of a boiler, an elastic fluid turbine, conduit means for conducting elastic fluid from said boiler to said turbine, an admission valve for said turbine, a second turbine adapted to be driven by the exhaust fluid from said first turbine, an admission valve for controlling the flow of fluid to said second turbine, means for simultaneously adjusting the admission valves of said first and second turbines in accordance with a condition of load on said second turbine, and means automatically operable in response to a condition of operation of said boiler for varying the relative amount of adjustment of said first turbine admission valve with respect to a predetermined adjustment of said second turbine admission valve.

PAUL H. KNOWLTON, JR.
